DESIGN FOR AN EXTENSIBLE BAND FOR A
WATCH BRACELET OR SIMILAR ARTICLEHans J. Duester, Chicago, Ill., assignor to himself
and John Major, Chicago, Ill.

Application August 20, 1948, Serial No. 148,213

Term of patent 14 years

(Cl. D45—4)

To all whom it may concern:

Be it known that I, Hans J. Duester, a citizen of the United States residing at Chicago, in the county of Cook and State of Illinois, have invented a new, original, and ornamental Design for an Extensible Band for a Watch Bracelet or Similar Article, of which the following is a specification, reference being had to the accompanying drawings, forming a part thereof.

In the drawings:

Figure 1 is a top plan view of an extensible band for a watch bracelet or similar article showing my new design, the coiled portions of the band shown in full lines being repeated throughout the length of the band as indicated by the broken lines;

Figure 2 is a bottom plan view of the band as shown in Figure 1;

Figure 3 is an enlarged fragmentary view of a section of the coiled portion of the band illustrating the details of the design;

Figure 4 is an enlarged cross sectional view taken on the line 4—4 of Figure 3.

I claim:

The ornamental design for an extensible band for a watch bracelet or similar article, as shown and described.

HANS J. DUESTER.
